ATTORNEY

UNITED STATES PATENT OFFICE

HENRY S. JACOBS, OF MARION, OHIO, ASSIGNOR TO THE MARION STEAM SHOVEL COMPANY, OF MARION, OHIO, A CORPORATION OF OHIO

HOIST CONTROL SYSTEM FOR ELECTRIC SHOVELS

Application filed April 26, 1929. Serial No. 355,362.

It is the object of my invention to provide an electrical control system particularly adapted for electrically driven excavating equipment, such as shovels.

5 It is the object of my invention to provide an electrical control system for the hoisting of the dipper and for the crowding of the dipper into the material to be hoisted so that the motion which raises the dipper through 10 the bank and the motion which forces the dipper into the bank will be effected with electrical equipment having the following desired characteristics.

Such characteristics are the capacity for 15 very quick starting, that is, high speed acceleration of the electrical equipment; the bringing of the hoist or crowd motor up to speed in the most satisfactory fashion; the 20 operation of the hoist or the crowd mechanism by a single controller with a single handle so that one continuous movement of the operator will bring the shovel into full 25 operation; the maintenance of very high speeds when the load is light so as to lift the light load at high speed; the ability to lift a heavy load at low speed; and the ability 30 to exert the maximum pull at stall without undue mechanical or electrical strains.

It is a further object to provide equipment 35 having such characteristics with the accompanying characteristics of long life of the motors, decreased maintenance costs, decreased lost time, decreased power consumption 40 per unit of work done and a better relationship between the speed and torque delivered by the motors.

It is a further object to provide equipment 45 in which the time lag of protective electrical equipment heretofore used is largely eliminated.

It is a further object of my invention to 50 provide electrical control equipment of such small size and compact nature that there is not only economy in cost but in the space 55 occupied which is a material factor on an electric shovel where the floor space is extremely limited.

It is a particular object of my invention to 60 reduce the extent of excess heating of the control equipment.

It is an object to provide for smoother acceleration of the motor, better commutation of the motor and generator and less severe mechanical and electrical strains on the equipment.

In particular, it is my object to furnish a low inductive generator shunt field with a corresponding low resistance field winding; means for reducing voltage of the generator immediately prior to placing the motor on the circuit in order to decrease the current inrush of the motor when the motor armature circuit is closed; and the raising of the generator voltage by proper field control while simultaneously cutting out starting resistance. The results of these particular objects are the utilization of a generator circuit, a motor circuit and a field bleeder circuit preferably associated with permanent resistors and a variable armature resistance in the motor circuit.

It is my object to prevent poor commutation on the motor and generator; to prevent excessive and unnecessary heating of both the motor and generator; to prevent excessive mechanical and electrical strains; to make possible a decreased amount of ohmic resistance in the starting resistor; to make possible a more rugged mechanical resistor construction for a given space and which can use 65 cheaper material and to provide higher speeds and higher generator voltage with the same starting resistance and same mechanical and electrical strains.

It is my object to provide a field bleeder circuit improved upon the generator and motor circuit for suitably raising and lowering the voltage in the circuit.

It is my object to employ a suitable resistor to prevent sudden inrushes of current in the motor when the controller is moved quickly to cut out all starting resistance, and it is my object to provide a suitable resistor for governing the amount of generator voltage reduction when the primary switches are closed.

It is my object to provide a balancing of voltages through the equipment and circuits I provide for effecting the above objects.

Referring to the drawing:

Figure 1 is a wiring diagram showing the arrangement of the hoist and crowd circuit in the "at rest" position with the generator standing alone not due to the operation of the generator being the motor, and

Figure 2 is a similar view showing the several switches closed and indicating by arrows the direction of current flow.

The subject matter of this application is shown and described but not claimed in Patent No. 1,858,048, granted November 29, 1932, and in an application filed by me April 26, 1929, Serial No. 346,264.

Construction and operation of excavating shovels

It is well known that in order to determine the problems involved in the solution of this problem of controlling proper automatic control parts for a power shovel, it is necessary to start the shovel and for it to move the earth equipment very quickly and to move the earth equipment at a light load at high speed and to move the earth equipment at a low speed and to move the earth equipment at a full load without undue difficulty. In order to do this, it is necessary to determine the conditions under which the shovel is to be used.

The shovel should be called upon to deliver maximum power. It may be moving earth equipment at the maximum speed and in a condition of a record load. It may be called upon to deliver power practically to maximum speed at a speed with which it can move the earth equipment with which it can move the earth equipment to full light loads at high speed and to move the earth equipment at low speed and to extract the earth equipment from the deepest bucket to the highest point in the bank, determine

the conditions under which the controlled shovel is to be used and to determine the electrical problems involved in the control of the equipment under the conditions of use. There is a very important consideration in the starting lag in the motor. In the case of the motive electrical equipment, the mechanical and magnetic characteristics of the motor, such a time lag is necessary in the old type of equipment to insure that the motor will not immediately over-speed. If the motor will continue to spin excessively, it would be harmful, as that would materially slow down the operation of the motor and reduce production. Thus a time lag is necessary to insure the protective equipment will not prevent unnecessary delays. It has been found that it has been necessary to have a time lag in the motor in order to permit the motor to accelerate to be regulated to the required speed, but this requires a motor with a high field capable of developing a current from seventy-five to eighty percent of the generator armature voltage. This type of motor is objectionable, as it is highly inductive and is very slow in its response to

changes. Hence, when the generator is connected with the motor through the armature resistor and this resistor is cut out step by step, generator voltage does not fall off quickly due to the cutting out of the resistor to any practical extent but it sends enough additional current through the circuit to cause the voltage drop of the circuit with the reduced resistance in it equal to approximately the voltage of the generator before this resistance was cut out. This means a rather considerable increase in circuit current when the amount of resistance cut out is a relatively large percentage of the resistance of the circuit. Hence, when the motor has completed its acceleration and is carrying its load, sudden fluctuations of load on the motor are transmitted to the generator causing fluctuations of current delivered by the generator to the motor similar to those fluctuations of current caused by the sudden cutting out of resistance in starting the motor which gives the generator the tendency to send sudden increases of current into the motor in excess of what the action demands if the field of the generator is capable of acting instantaneously.

Consequently, as a solution of this problem, if the total resistance of the generator and leads is increased and the starting resistance (the armature resistance which is cut out step by step) is left the same, it follows that the inrush current will be smaller than the inrush current obtained when the resistance of the generator and leads is not increased. This results in smoother and better commutation of the motor and generator and less severe mechanical and electrical strains on the equipment.

If the voltage of the generator is reduced before connecting it to the motor through the starting resistor for the certain inrush current the amount of resistance required will be less.

If, immediately after connecting the motor to the generator through the starting resistance, the motor begins to accelerate, the inrush current will tend to fall off as the counter voltage of the motor increases.

However, if the motor handles the inrush current and if the generator voltage rises in value along with the rise in the counter voltage generated, the inrush current will not fall off but will be maintained constant in value. This will produce a constant acceleration torque in the motor.

If, on the other hand, the rise in the voltage of the generator is greater than the rise in the voltage in the motor, the inrush current will tend to fall off but to a lesser degree, where the generator voltage is maintained constant. The best practical condition of acceleration for this type of control would then be to have the current fall off just sufficient so that when the next small step of

starting resistance is cut out the inrush current would at that time, be equal to the initial inrush current. The following steps of resistance can then be cut out in exactly the same fashion until all the resistance has been cut out except that which constitutes the permanent resistance of the circuit.

Hence, I find that by providing a generator circuit, a motor circuit connected thereto, a bleeder circuit connected into the motor and the generator circuit and resistance of permanent character in association with the variable resistor in the motor field circuit, I am enabled to so adjust the conditions of the circuits as to secure quick starting, high speed with light loads, low speed with heavy loads and maximum pull at stall.

Generator circuit

20 The generator circuit is composed of a generator G. This generator has connected thereto by the wire 1 a series field 2 which, in turn, has connected to it by the terminal 3 a resistor, designated 4, that is connected by an intermediate wire 5 with the other section 6 of the resistor that is, in turn, connected to the shunt field 7 that is, in turn, connected by the wire 8 and wire 9 to the commutating field 10 of the generator G to which it is attached by the wire 11. The generator is driven by any form of prime mover designated 12. While the shovel is operating the circuit just described is always hot and the current is traveling in the direction indicated by the arrows. This is the generator circuit.

Motor circuit

HM indicates the hoist motor. The hoist motor is provided on one side with the lead 13 that connects the motor to its commutating field 14. This commutating field is connected to the permanent resistor 15. This side of the motor circuit is adapted to be connected to the generator circuit by the primary switch AA. This switch is a reversible switch. It is interconnected with and adapted to be simultaneously operated with the second of the primary switches, designated A.

Bleeder circuit

The bleeder circuit is connected by the lead 16 to the hoist motor. On the other side it is connected to the lead 17 that forms a part of the bleeder circuit, the other side of which is connected by the wire 18 to the terminal 19 in the generator circuit. Between the wires 17 and 18 is located the permanent resistance 20. This combined motor commutation field circuit and the bleeder circuit having been simultaneously connected to one another and to the generator circuit by the closing of the primary switches AA and A are now in a position to be connected to the series field motor circuit and the variable resistance.

Motor series field circuit and variable resistance

The switch B is the secondary switch which is closed after the switches A and AA have been simultaneously closed. AA is a reversible switch. Upon the closing of the switch B the bleeder circuit and the commutating field circuit of the motor have been connected with the series field circuit of the motor. Thereupon, the lead 21 connects the variable resistance 22. This resistance is provided with the slide wire base terminal 23 and typical stages of resistance 24, 25, 26, 27, 28 and 29. 30 indicates the slide wire contact member. 31 indicates the lead that connects this circuit into the series field 32 of the motor and 33 indicates the lead that connects the series field to the terminal 3 in the generator circuit.

The variable resistance 22 is a progressive resistance, the resistance steps increasing as the movable member 30 progresses from 29 to 23 to thereby give a more nearly uniform heating in the controller.

Field bleeder circuit

The addition to the circuits of the sections 17, resistor 20 and 18 constitutes the bleeder circuit proper but when the bleed circuit operates it embraces and is composed of, in effect, the standard motor commutating circuit heretofore described, such as from AA, 15, 14, 13, HM and 16 with switch A.

Current directions

The current in the generator circuit never changes direction. When all switches are closed, due to the difference in potential between the points 34 and 19 the current flows from 19 through 18, 20, 17, A, 34, 16, HM, 13, 14, 15, AA at which time the variable resistor slide wire 30 is not passed beyond the medium point of the variable resistor 22 but upon passing beyond that point, as will be herein-after described, the current divides so that a part of it travels in the direction from 34, 16, HM, 13, 14, 15, AA, to the generator circuit and on the other side travels up from 34 through switch A, 17, resistor 20, 18, 19 and into the generator circuit for the purposes hereinafter described.

The series field circuit of the motor is arranged so that the current travels in the direction 33, 32, 31, 29 through the resistor 22, 21, switch B and thence into the circuits hereinbefore mentioned and described.

Relative voltages

At certain important points in the system, the voltages vary and this difference in potential at these points is essential to the operation of my circuits and apparatus. The voltages I indicate are merely typical and not exclusive. Assuming a given motor load of

generator motor, the conditions are about as follows as to voltage in a relative sense.

0.4 generator voltage

In the starting position the switch AA will connect voltage point A, 150 volts, point 16, 150 volts, point 3, 300 volts, and point 7a, 300 volts, with the current direction as indicated in the generator circuit.

When the motor switch is closed, and the motor switch is closed, the voltage at 3 is 150 volts, at 16 is 150 volts, at AA and 7a, zero volts, and at points A and 3a at practically zero voltage. The current is then flowing, clockwise, through point 19 through resistor 20 and then down through the motor field, back to the point 19 or circuit of 7a.

The voltage of the generator is quite low and the maximum generated current is required to limit the available maximum current in the field through the starting variable resistor, reducing the electrical overexcitation strain to the minimum.

Starting position. Closing of switch AA and opening of switch B

When the motor switch is closed, point 3a, zero voltage, point AA, zero voltage, point 7a, zero voltage, point 3, 300 volts, and point A, 200 volts. If switch B is closed, the motor field is shorted.

Starting position. Adjustment of position of slide wire contact on variable resistor

Assuming the slide wire contact 30 is about halfway across the starting variable resistor, the voltage of the respective points will be as follows:

Point 3, 300 volts, point 15, 150 volts, switch AA at point 3a, zero voltage, at point 34, 150 volts, the rest of the circuit, 150 volts. No current will be flowing through resistor 20. The voltage across the slide wire will be the same in the two halves of the circuit but since the voltage at 34 is 150, and at 15 is 150, no current will be flowing through the resistor 20. The current in the motor field will remain the same as the current in the circuit in this starting position. On the other hand, the current through 16 and the motor motor field current is flowing clockwise to the generator circuit.

When the switch B is closed, the voltage goes to zero at 3a, and the voltage at 34 goes to 300.

When the switch B is closed, the voltage goes from the halfway point on the variable resistor to 34, for example, 20 over to 30, the voltage at 34 is 300, the voltage at 15, 150 volts, at 16, 150 volts, and the voltage, and current in the motor field will be the result that the current conditions are as above in the preceding paragraph except that the greater voltage at 34 and the lesser voltage at

19 current is flowing through 20 from 34 to 19 as well as from 34 through 16 to the motor field and thence to the generator circuit.

The purposes of these relative voltages will be apparent from the following description.

Control of the switch

For the purpose of clearness the diagrams do not show the switches interconnected but in practice, a single controller for the field circuit is provided with a single controller handle which operates the switches AA and AA to close them simultaneously. Then the switch B is closed by further movement of the handle, and then the slide wire contact member 30 is moved over the variable resistance 20 from point to point by further movement of the controller handle.

Nature of the equipment

The generator is a shunt-wound generator, preferably with a drooping voltage characteristic. Depending upon the type of prime mover used to drive the generator, it is sometimes advisable to add the light series field 2. If the speed regulation is good as compared with that of the reduction motor, a suitable for use as the prime mover, this series field is usually unnecessary and a straight shunt generator is used.

Stages of operation

The first step is to prepare for the load by closing the switches AA and A simultaneously, thus bleeding current from the generator field through the bleed circuit to reduce the generator voltage in preparation for taking up the load.

Half of the current in 4 is bled from the generator field circuit and by passing through the motor armature and the resistor 16. Therefore, it is bled across the generator field for the purpose of reducing the field strength of the generator to reduce maximum current inrush on starting.

Then close the switch B to get current to start the motor HFM and to bring in the motor series field circuit.

Thereafter, the motor generates current and voltage raising the voltage at the switch B so that current flow from 19 to switch B will decrease and the current in resistor 20 is decreased so that the generator voltage tends to rise because of the reduction in the field.

The start current position is such that the current will flow in the motor HFM. Consequently, the motor HFM tends to accelerate and the voltage tends to rise in it. The field strength of the generator rises due to increasing voltage as the voltage at B tends to rise more rapidly than at 19 whose value is more or less constant.

When about one-half of the resistance 20

is cut out of the circuit the voltage at 34 equals the voltage at 19 and no current flows through the resistance 20. This gives the same operation as though the bleeder circuit 17, 20 and 18 were cut out.

As the slide wire 30 proceeds from the middle point of the resistance 22 towards 29 the bleeder circuit raises the generator circuit voltage above normal to give the motor a higher maximum speed than otherwise possible.

The motor has now been given the proper torque. It is now necessary to give the motor speed. This is done by cutting out the 15 steps of resistance as indicated which raises the voltage applied to the motor causing it to generate a higher voltage and to rotate at higher speeds as the counter voltage of the motor rises and the difference in voltage between 20 34 and 19 decreases which reduces the amount of current shunted out of field 7 thereby raising the generator voltage. The increasing voltage applied to the motor for increasing the speed is then due to a combination of cutting out the resistance 22 and the raising of the generator voltage due to the bleeder circuit connections.

Hoist motor stop operation

20 To stop the hoist motor the reverse operation of handling the starting switches is effected. This is done by first cutting in, in succession, all parts of the variable resistance 22 until the slide wire 30 has reached 35 23. Switch B is then opened and then switches A and AA are opened together.

Resistance 15

When the permanent resistance 15 is in 40 line the heating on the hoist controller is decreased by the reduction of the arc. The presence of the resistance 15 gives the same effect as a greater number of steps in the resistance 22 with a decreased arc without increasing the size or changing the design of the controller. The greater the number of 45 steps the smaller the arc so that I secure the same effect in a simpler, more compact and cheaper manner by the utilization of the resistance 15 as located. It is possible to employ a smaller and more compact controller of less expensive character while at the same time, decreasing the heating of material and increasing the life of the entire equipment.

Characteristics of generator field 7

In accomplishing my invention, I employ 50 a low inductive and low resistance field winding of the generator, such as 7. I prefer to 60 use a generator with a drooping voltage characteristic.

Switches AA and field bleeder circuit

The arrangement of the switches AA and 65 the field bleeder circuit is for the purpose of

reducing voltage for the generator immediately prior to throwing the hoist motor on the circuit in order to decrease the current inrush of the hoist motor when its armature circuit is closed by closing the switch B. 70 This has the following factors:

(1) Bad commutation on the hoist motor and generator is eliminated.

(2) The arrangement prevents excessive and unnecessary heating of both the generator 75 and the hoist motor.

(3) It prevents excessive mechanical and electrical strains.

(4) It makes possible a decreased amount 80 of resistance in the starting resistor.

(5) It makes possible a more rugged mechanical resistor construction for a given space and makes possible the use of cheaper material.

(6) It makes possible higher speeds and 85 higher generator voltage with the same starting resistance and with the same mechanical and electrical strains.

Switch B and the slide wire variable resistance

The purpose of this arrangement of switch B and the slide wire variable resistance is to begin raising the generator voltage by field control while simultaneously cutting out the starting resistor. The bleeder circuit is used to raise as well as to lower voltage at the switch B.

Resistors 15 and 20

The resistor 15 is used to prevent the inrush of current on the motor when the controller is moved quickly to cut out all the resistance. Resistor 15 for that purpose is made equal to the resistance of the motor.

The resistor 20 governs the amount of the 105 generator voltage reduction when switches A and AA are closed.

While the apparatus is designed primarily for the operation and functions which have been described I wish it to be understood that the so-called bleeder circuit (17—18—19) is also capable of functioning as a generator field strengthening circuit. When it is to be so used the switch B is closed before the switch A is closed, thus throwing the motor on the line before the resistor 20 is cut in. The cutting in of the resistor 20 after the motor has attained speed reduces the effective resistance in the generator shunt field circuit and thereby strengthens the generator shunt field.

It will be understood that I desire to comprehend within my invention such modifications as may be necessary to adapt it to varying conditions and uses.

Having thus fully described my invention, what I claim as new and desire to secure by Letters Patent, is:

1. In a motor control system, the com- 130

1. In combination with a generator a circuit therefor including a self-excited shunt field and a resistor in series with said shunt field, or a motor having an armature, a series field connected with one side of said generator circuit, and a resistor connected with the other side of said generator circuit, having a series field connected with one side of said generator circuit, and a resistor connected with the other side of said generator circuit, a resistor connected with the generator shunt circuit between said shunt field winding and said resistor in said generator circuit, and means for connecting said resistor with the last mentioned motor circuit on that side of the motor armature with which the motor series field is connected.

2. In a motor control system, the combination with a generator and a circuit therefor including a self-excited shunt field and a resistor in series with said shunt field, of a motor operated thereby having a series field connected with that side of said generator circuit, with which said resistor is connected, and an armature connected with the other side of said generator circuit, a variable resistor in series with said motor series field, a resistor connected with said generator shunt circuit between said shunt field winding and said resistor in said generator circuit, and operative means for connecting the last mentioned resistor and said variable resistor one side of the motor with said motor armature.

3. In a motor control system, the combination with a generator and a circuit therefor including a self-excited shunt field and a resistor in series with said shunt field, of a motor operated thereby having a series field connected with that side of said generator circuit, with which said resistor is connected, and an armature connected with the other side of said generator circuit, a resistor connected with the resistor in said generator circuit at a point between the ends thereof, and means for connecting the last mentioned resistor and the circuit on that side of the motor armature with which said motor series field is connected.

4. In a motor control system the combination with a self-excited shunt generator having a permanent resistor in its shunt field circuit, of a series motor operated thereby, having a series field winding and a variable resistance in series therewith connected across part of a permanent field resistor, the last mentioned resistor connected across the other side of a permanent resistor and the generator shunt field winding.

5. In a motor control system, the combination with a self-excited shunt generator having a permanent resistor in its shunt field circuit, of a second resistor connected with said generator resistor, a series motor operated by said generator and having a series field winding and a variable resistor in series therewith connected across part of said permanent field resistor through said second re-

sistor, and having its armature connected across the other part of said permanent resistor and the generator field winding through said second resistor.

6. In a motor control system, the combination with a self-excited shunt generator having a permanent resistor in its shunt field circuit, of a second resistor connected with said generator resistor, a series motor operated by said generator and having a series field winding and a variable resistor in series therewith connected across part of said permanent field resistor through said second resistor and having its armature connected across the other part of said permanent resistor and the generator field winding through said second resistor, and operative means to separately control said connections.

7. In combination with a generator, and a circuit therefor, including a generator shunt field, of a motor having an armature, a series field and a variable resistance in series with said series field, means for first connecting said motor armature across a portion of said generator shunt field circuit to reduce the generator voltage and then connecting said motor series field with said generator circuit in advance of said generator shunt field and gradually cutting out said variable resistance and increasing the current flow through the generator field.

8. In combination with a generator, and a circuit therefor including a generator shunt field and a resistor, of a motor having an armature, a series field and a variable resistance in circuit with said series field, a bleeder circuit connected with said generator resistance between the ends of the latter and including a resistor, means for connecting said motor armature with said bleeder circuit and with said generator circuit on that side of said generator shunt field opposite said generator resistance, thereby passing a portion of the current about said generator shunt field and reducing the generator voltage, and means for connecting said motor series field with said bleeder circuit and for cutting out the variable resistance.

9. In a motor control system, the combination with a generator and a circuit therefor including a resistor and a shunt field, of a motor armature and a circuit therefor including a resistor connected with one side of said generator circuit, a bleeder circuit connected into the resistor in said generator shunt field circuit and including a permanent resistor, a switch for connecting said bleeder circuit to the motor armature circuit, a series motor field connected to the other side of said generator circuit, a variable resistance in circuit with said motor series field, and a switch for connecting said motor series field with the motor armature circuit between the motor and the switch which connects the armature circuit and the bleeder circuit.

10. In combination with a generator circuit comprising a generator having in circuit a series field, a resistor, a shunt field and a commutating field, a series motor field circuit having in series a series field and a variable resistance, said circuit being permanently connected into the generator circuit at a point between the generator and the generator resistor, a bleeder circuit including a permanent resistor connected permanently with the resistor of the generator circuit and adapted to be connected to the series motor field circuit, a motor commutating field circuit comprising an armature, a commutating field and a permanent resistor, switches connecting the commutating field circuit to the generator circuit and to the bleeder circuit, and a switch for connecting the motor series field circuit to the bleeder circuit and the commutating motor field circuit so connected.

11. In a motor control system in combination with a generator and a circuit therefor, including a generator shunt field winding and a resistance, of a motor having a series field winding connected with that side of said generator circuit with which said generator resistance is connected, an armature connected to the other side of said generator, a generator field strengthening circuit connected with said generator resistance, and means for connecting said generator field strengthening circuit with that side of said motor armature with which said motor series field winding is connected.

12. In a motor control system, the combination with a generator and a circuit therefor including a generator shunt field winding, of a motor having a series field winding connected to said generator circuit on one side of said shunt field winding and an armature connected to said generator circuit on the other side of said shunt field winding, a variable resistor adapted to be connected in series with said motor armature, a resistor having one side thereof connected to some point in the generator shunt field circuit on that side of said generator shunt field winding with which said motor series field is con-

nected and having the other side thereof adapted to be connected to the motor circuit on that side of the motor armature with which the motor series field is connected, and operable means for connecting said variable resistor and the last mentioned resistor one after the other to said motor armature.

13. In a motor control system, the combination with a generator and a circuit therefor including a generator shunt field winding, of a motor having a series field winding connected to said generator circuit on one side of said shunt field winding and an armature connected to said generator circuit on the other side of said shunt field winding, a variable resistor adapted to be connected in series with said motor armature, a resistor having one side thereof connected to some point in the generator shunt field circuit on that side of said generator shunt field winding with which said motor series field is connected and having the other side thereof adapted to be connected to the motor circuit between the variable resistor and the motor armature, and operable means for first connecting the last mentioned resistor with said motor armature and thereafter connecting said variable resistor with said motor armature.

14. In a motor control system, the combination with a generator and a circuit therefor, including an armature, a shunt field and a permanent resistor between said generator and said shunt field, of a motor series field having a circuit connected with that side of said generator circuit with which said resistor is connected, a motor armature and a circuit therefor connected with the other side of said generator circuit, means to bleed current from the generator circuit and by-pass it through the motor armature circuit and through said permanent resistor, whereby current is shunted around the generator shunt field for the purpose of reducing the field strength of the generator to reduce maximum in-rush current when starting the motor.

In testimony whereof, I affix my signature.
